UNITED STATES PATENT OFFICE.

CHARLES HOTH, OF WAUKON, IOWA.

DELIVERY APPLIANCE.

1,018,497.

Specification of Letters Patent. Patented Feb. 27. 1912.

Application filed August 17, 1911. Serial No. 644,580.

To all whom it may concern:—

Be it known that I, CHARLES HOTH, a citizen of the United States, residing at Waukon, in the county of Allamakee and State 5 of Iowa, have invented certain new and useful Improvements in Delivery Appliances; and I do hereby declare the following to be a full, clear, and exact description of the invention, such as will enable others skilled in 10 the art to which it appertains to make and use the same.

This invention relates to delivery appliances and more particularly delivery appliances for delivering hay, etc., to either 15 side of the barn, hay-loft or like structure.

An object of the invention is to provide a delivery appliance mounted upon suitable tracks among the rafters of the structure and movable along the length of the building, 20 said appliance being of such construction and operation that it may be readily tilted to either side to deliver hay, etc., delivered thereupon by the carrier thereabove, to either side of the building as may be desired 25 so as to fill every portion of the structure.

Another object is to provide a delivery appliance of this nature which may be installed in any structure in which it is desired 30 to store hay or the like and which will be separate and independent of the carrier.

Other objects and advantages will be hereinafter set forth and pointed out in the specification and claim.

In the accompanying drawings which are made a part of this application, Figure 1 is a vertical cross sectional view, through the upper portion of the framework of an ordinary barn or hay loft, showing my delivery appliance suspended upon its track secured to cross braces or beams fastened to the rafters, Fig. 2 is an enlarged fragmentary view, showing one corner of the framework of the delivery appliance and one 45 of the wheels or rollers of said framework in position upon its rail, Fig. 3 is a vertical sectional view on the line 3—3 of Fig. 1, the rafters not being shown, and Fig. 4 is an end view of the delivery appliance 50 moved from its track.

Referring more particularly to the drawings in which similar reference numerals designate corresponding parts throughout the several views 1 represents the track rails 55 which are substantially of L-shaped form in cross section and are secured to the beams

2 adjacent the rafters 3 and preferably extending longitudinally of the structure. The track rails 1 are fastened to the beams 2 and extend in a horizontal direction with their long sides or wide sides directed at an angle toward the lower side edges of the building while their narrow edges are at right angles thereto, and extend toward the sloping side rafters 3 for supporting thereupon the wheels or rollers 4 mounted upon suitable pins or shafts 5. The shafts 5 are mounted in and extend from the upper portions of the upwardly extending corner posts 6 of the framework of the movable 60 delivery appliance. The lower ends of the corner posts 6 are connected by the horizontal end strips 7 while the upper ends of said corner posts are connected and braced by the bracing rods or strips 8. At the 65 meeting ends of the corner posts 6 and the end strip 7 and at the junction of the ends of the bracing rods or strips 8 with the upper ends of the corner posts 6, are provided corner irons 9 to strengthen the parts at 70 these connections. Upon the upper edge of each of the end strips 7 about midway the ends thereof, are the bearing brackets 10 which are adapted to receive the opposite 75 ends of the rock shaft 11, extending longitudinally of the framework. A suitable rack 12 is secured upon the under side of each end strip 7 below the bearing brackets 10, the purpose of which will presently appear. A suitable cradle or rocking bed 80 composed of the spaced strips 13 secured upon the connecting strips 14 is provided upon its under side with the shaft 11 (previously mentioned), the main portion of which is flat and secured to the under side 85 of the tilting bed by screws or other suitable means, while the ends of the shaft 11 are reduced and rounded to be received within the bearing brackets 10. Upon one 90 end or, if desired, both ends, is positioned a lever 15 which extends downwardly and carries a spring actuated dog 16 for engagement with the teeth of the rack 12 upon the adjacent end strip 7. As the lever 15 is rigid with the shaft 11 and the dog 16 is 95 engaged with the teeth of the rack 12, the cradle or rocking bed will be held in position, either tilted or in its normal horizontal 100 position, as will be readily understood.

It will be understood that any form of 110 carrier or sling may be positioned and operated above the delivery appliance and the

2
latter moved so as to receive hay or other like material from the carrier or sling and will deposit the same in any portion of the structure desired. It being understood that the delivery appliance may be readily moved upon its track and tilted so as to guide the material to either side of the enclosure. When it is desired to tilt the cradle or bed or to return the same to a horizontal position, the lever 15 is grasped and the dog disengaged from the rack 12 by pressing the finger 17 against the handle end of the lever 15, as will be clearly understood.

15 In Fig. 4, I have shown the wheels or rollers 4 as being mounted upon the outwardly directed ends of the shafts 18, the opposite ends of which are flattened and secured against the upper ends of the corner posts 6. In this view I have also shown operating cords having their upper ends secured to the lever 16 and to the opposite ends of certain of the spaced strips 13. The operating cords are designated by the numeral 25 19 and are connected with the lever 16 and the ends of the strips 13 by means of rings or eye-screws 20. By the use of these cords 19, the device may be operated by a person some distance away from the delivery appliance to good effect.

Thus it will be seen that I have provided a delivery appliance which will deliver hay, etc., to any portion of a structure desired while filling the same with the material to be stored therein without the necessity of a workman moving along the rafters with the device to guide the material from the delivery appliance as desired, the automatic cradle or tilting bed serving this purpose.

It will be understood when the material is to be delivered to the central portion of the structure, the delivery appliance is moved along its track to allow the carrier or sling to drop said material to the center of the structure.

Owing to the extreme simplicity of the construction and operation of this device, it may be manufactured, installed and operated at an extremely small cost.

What I claim is:

A delivery appliance for delivering hay to the sides of a structure comprising a tilting bed having a shaft secured to the under side thereof, a framework including end pieces having corner posts extending upwardly therefrom, cross strips connected to the corner posts near the upper ends thereof, means for bracing the corner post against the end pieces, the shaft having its opposite ends mounted for rotation upon the end pieces, the bed being positioned between the end pieces and adapted to be tilted to opposite sides, means for tilting the bed, means secured to said shaft and adapted to coöperate with means carried by the end pieces to lock said bed at different angles, the framework and bed being suspended within the structure and adapted for movement longitudinally thereof, and a track upon which the device may be moved within the structure.

In testimony whereof I have signed my name to this specification in the presence of two subscribing witnesses.

CHARLES HOTH.
